DESIGN FOR ICE TONGS

Arthur D. Brooks, Cleveland, Ohio, assignor to
Eaton Detroit Metal Company, Cleveland,
Ohio, a corporation of Ohio

Application August 21, 1936, Serial No. 64,506

Term of patent 3½ years

To all whom it may concern:

Be it known that I, Arthur D. Brooks, a citizen of the United States, residing at Cleveland, in the county of Cuyahoga and State of Ohio, have invented a new, original, and ornamental Design for Ice Tongs, of which the following is a specification, reference being had to the accompanying drawing, forming part thereof, in which

Fig. 1 is a perspective view of ice tongs showing my new design;

Fig. 2 is a section on the line 2—2 of Fig. 1, and
Fig. 3 is a section on the line 3—3 of Fig. 1.

I claim:

The ornamental design for ice tongs, as shown.

ARTHUR D. BROOKS.
